Primary Examiner — Steven J Czyz(74) *Attorney, Agent, or Firm* — Patterson Thuente
Pedersen, PA(57) **CLAIM**

The ornamental design for a lock device, as shown and described.

DESCRIPTION

FIG. 1 is a front perspective view of a lock device;
 FIG. 2 is a back perspective view thereof;
 FIG. 3 is a front view thereof;
 FIG. 4 is a rear view thereof;
 FIG. 5 is a top view thereof;
 FIG. 6 is a bottom view thereof;
 FIG. 7 is a right side view thereof; and,
 FIG. 8 is a left side view thereof.
